ELECTRIC MOTOR

Glenn D. Willits, Grabill, Ind., assignor to General Electric Company, a corporation of New York

Filed Dec. 26, 1962, Ser. No. 72,943

Term of patent 14 years

(Cl. D26—5)

Fig. 1.

Fig. 2.

Fig. 3.

FIG. 1 is a perspective view of an electric motor showing my new design;

FIG. 2 is a side elevational view of the electric motor of FIG. 1; and

FIG. 3 is a rear elevational view as seen from the bottom of FIG. 1.

The dominant features of the design reside in the portions as shown in full lines and are characterized primarily by a motor cover plate for a cylindrical motor housing which is shaped as shown by the full lines.

I claim:

The ornamental design for an electric motor, as substantially shown and described.
